UNITED STATES PATENT OFFICE.

JOHN MURRAY, OF LONDON, ENGLAND.

MACHINE FOR FLATTENING OR STRAIGHTENING BOOK COVERS OR CASES AND THE LIKE.

1,424,583.

Specification of Letters Patent. Patented Aug. 1, 1922.

Application filed June 20, 1921. Serial No. 478,898.

(GRANTED UNDER THE PROVISIONS OF THE ACT OF MARCH 3, 1921, 41 STAT. L. 1313.)

To all whom it may concern:

Be it known that I, JOHN MURRAY, a subject of the King of Great Britain and Ireland, and a resident of London, England, 5 engineer, have invented certain new and useful Machines for Flattening or Straightening Book Covers or Cases and the like (for which I have filed an application in England, No. 2516, January 27, 1920, Patent No. 162,380), of which the following is 10 the specification.

In book-binding, if book-covers or cases covered with cloth or other material are kept until the glue securing that covering 15 material is dry, the sides of the boards upon which the material is attached curl up owing to its contraction, and the boards assume a hollow or basin-like shape. For the subsequent operations upon the cases, it is necessary that they should be flat. Usually 20 they are flattened by hand, which not only is a lengthy operation, but often leads to damage owing to the rough treatment the cases receive.

25 The invention has for its object to provide a simple machine for effectively flattening the cases in a uniform manner, without risk of damage and with the expenditure of very much less time.

30 A machine made according to the invention comprises essentially rolls parallel with one another and with their axes lying in the apices of a common triangle. The rolls are sufficiently closely adjacent to engage a 35 case fed between them and thus act after the manner of a sheet-metal straightening machine. But, as the bending effect (by which straightening is attained) is due to two of the rolls folding the case around the 40 periphery of the third roll, it is apparent that the entering and leaving edges will not be effectively bent for a distance equal to the distance between the points of contact between each of the two rolls and what may 45 be termed the intermediate roll. In order to obviate this disability, and to ensure that substantially the whole of the case shall be subjected to this reverse bending (which has the effect of straightening) the two 50 bending rolls are each subdivided into a series of short rolls or collars, the collars on one roll intermeshing with the collars of the other—that is to say, the collars of each

roll being set into the spaces between the collars of the other roll. Alternatively, the 55 rolls may have cut upon them comparatively deep square screw threads of similar hand and may be so set that the threads intermesh with one another.

Thus the axes of the rolls may be brought 60 much nearer to one another, and correspondingly their points of contact upon the intermediate roll (which is preferably, of course, of one diameter throughout) are brought very much nearer together. The 65 rolls are, of course, mounted in adjustable, and one or more of them in spring-loaded bearings.

Any convenient means may be provided for presenting successive cases of a series 70 to the rolls in correct position for their straightening by reverse bending in their passage through them.

An example illustrative of one method of carrying out the invention is shewn on three 75 accompanying sheets of explanatory drawings, in which Figures 1, 2 and 3, sheets 1 and 2 are respectively a side elevation, an end elevation, and a plan of a complete machine, while Figures 4 and 5, sheet 3 shew the 80 straightening rolls to an enlarged scale in side (or end) elevation and plan respectively.

In this example the cases to be treated are arranged with their covered faces (that is 85 their hollow sides) downwards in a vertical pile within a hopper A. The hopper is formed by side members A¹, front members A² and base bars A³, on the latter of which the lowermost case in the hopper rests. The 90 various members of the hopper are supported by distance rods located between side plates B carried on a pedestal C. The front members A² are vertically adjustable by means of set screws A⁴ to vary the opening 95 at the base of the hopper through which the lowermost case is fed, and thus permit of cases of different thickness being handled. The cases are fed forward, one at a time, from the hopper A to the straightening rolls 100 D, E, F, by means of reciprocating pusher blocks G. The blocks G are secured to a slide G¹ which is mounted on transverse guide rods G² and provided on its underside with a rack G³. The rack G³ is engaged by 105 a toothed quadrant H adapted to be recipro-

cated by means of an arm H^1 , connecting rod H^2 , and crank shaft H^3 , the latter being driven from a main driving shaft D^1 on which the roll D is mounted.

5 The intermediate roll E which has a plain surface, is arranged above the bending rolls D , F and is maintained in resilient contact therewith by adjustable springs E^1 attached at one end to the axle bearings E^2 of the roll E , and at the other to the machine frame. In order to bring the axes of the rolls D , F as closely together as possible, and for the purposes hereinbefore described, each roll is subdivided into a series of short 10 collars D^2 , F^2 , the collars D^2 intermeshing with the spaces between the collars F^2 of the roll F . The roll D is supported in bearings in the side plates B while the roll F is journaled in bearings carried in the arms of 15 bell-crank levers F^1 fulcrumed in bushes on the driving shaft D^1 . Between the other ends of the levers F^1 and fixed points F^3 on the framing, are arranged springs F^4 in compression, the latter being adjustable and tending to maintain the periphery of the roll 20 F in contact with that of the rolls D and E . The shaft D^1 on which the roll D is mounted, forms the main driving shaft of the machine, the roll F being positively driven from this shaft by spur wheels J , while the roll E is purely a follower, driven by frictional contact from the other two rolls.

As each case is fed forward from the hopper A by the pusher blocks G , it is engaged 35 by the nip of the rolls D , E , and subjected to an upward bending action around the periphery of the roll E , the bending being thus applied in a direction opposite to that induced by the contraction of the glue securing 40 the covering material to the boards of the case. This neutralising effect, that is, the actual amount of upward bending to which the case is subjected, may be varied by adjustment of the springs E^1 . The cases 45 are discharged from the nip of the rolls E , F , to a receiver K supported on a distance rod between the side plates B . The receiver is downwardly inclined towards the front end K^1 and also towards the side K^2 thereof, thus providing for gravitational arrangement 50 of the discharged cases in an orderly pile within the receiver. The side plates B are adjustably mounted on the pedestal C to allow of the machine as a whole being 55 worked at any desired angle.

What I claim is:—

1. A machine for flattening or straightening book-covers or cases and the like com-

prising three parallel rolls with their axes passing through the apices of a common triangle, and so positioned relative to one another as to engage a case fed between them; intermeshing means between the peripheries of two of the rolls adapted to bring the axes thereof more closely adjacent and still permit of adjacent surfaces of the two rolls moving in opposite directions; means for feeding the cases successively to the rolls; and means for driving the rolls; as and for the purposes set forth. 60

2. A machine for flattening or straightening book covers or cases and the like, comprising three parallel rolls with their axes passing through the apices of a common triangle, and so positioned relative to one another as to engage a case fed between them, the faces of two of said rolls being circumferentially grooved and the ribs so formed intermeshing to bring the axes of said rolls more closely adjacent while still permitting the rolls to rotate in opposite directions, means for feeding the cases to the rolls and means for driving the rolls, substantially as and for the purpose set forth. 75

3. In the mechanism forming the subject-matter of claim 1 hereof, a hopper adapted to receive the cases to be handled face downwards in a vertical pile and apertured at its base to afford a discharge port through which one case at a time may be removed, means reciprocated parallel with and adjacent the bottom of the hopper and adapted to engage the lowermost case therein and convey it forward to the rolls, and a receiver beyond the rolls into which the straightened cases are discharged. 80

4. In the mechanism forming the subject-matter of claim 1 hereof, means for varying the neutralising or counter-bending action of the rolls, comprising tensionally adjustable springs constraining the periphery of one roll against that of the two intermeshing rolls, as set forth. 95

5. In the mechanism forming the subject-matter of claim 1 hereof, bell-crank levers fulcrumed on the axis of one intermeshing roll, the arms of the levers on one side of the fulcrum carrying the bearings of the other intermeshing roll, and the arms on the other side of the fulcrum so acted upon by springs in compression as to maintain the periphery of the latter roll in resilient contact with that of the other rolls, as set forth. 105

In testimony whereof I have signed my name to this specification. 115

JOHN MURRAY.
